UNITED STATES PATENT OFFICE.

INOS B. TANNER, OF CHICAGO, ILLINOIS, ASSIGNOR TO JOSEPH E. NELSON & SONS, OF CHICAGO, ILLINOIS, A COPARTNERSHIP COMPOSED OF JOHN E. NELSON AND WILLIAM H. NELSON.

LIQUID-TREATING APPARATUS.

Application filed May 4, 1923. Serial No. 636,743.

To all whom it may concern:

Be it known that I, INOS B. TANNER, citizen of the United States, residing at Chicago, in the county of Cook and State of Illinois, have invented a certain new and useful Improvement in Liquid-Treating Apparatus, of which the following is a full, clear, concise, and exact description.

My invention relates to liquid treating apparatus and in its preferred embodiment is an improvement upon the liquid treating apparatus disclosed in my United States Patent 1,407,499, dated February 21, 1922. The apparatus of that patent included a settling chamber, a chemical tank, a source of liquid under pressure, a pipe through which the liquid passes into the settling chamber for treatment, a chemical pipe also discharging into the settling chamber and having a port in its side through which chemical passes from the chemical tank into the pipe, a valve within the liquid pipe and controlling ports in said pipe and rising and falling according to the pressure of the liquid, and mechanism governed by said valve and governing the height of the chemical pipe, whereby the varying volumes of water and chemical will be in fixed proportion to secure the required reaction between the chemical and the materials that are to be precipitated out of the liquid. Water may readily be softened by means of such an equipment having the characteristics of the invention. The mechanism controlled by the valve within the liquid pipe included an intermediately pivoted lever connected at one end with the valve and at its other end with the chemical pipe.

In accordance with my present invention this lever is replaced by motion transmitting gearing including rack bars and gearing bringing them into motion transmitting relation, these rack bars having vertical movement parallel with the vertical movement of the chemical pipe. This mechanism is not only an improvement upon the apparatus disclosed in my aforesaid patent but is of such a nature that more than one chemical discharge pipe or other valve may be controlled by a single valve in the liquid pipe so that a plurality of differing chemicals may be admitted to the liquid where such are required to treat the liquid.

I will explain my invention more fully in

connection with the accompanying drawings in which Fig. 1 is a view illustrating a water softening plant equipped in accordance with the preferred embodiment of the invention, parts being shown in elevation and parts in section; Fig. 2 is a view illustrating a chemical tank and some of the equipment pertaining thereto, this figure being taken on line 2—2 of Fig. 4; Fig. 3 is a sectional view on line 3—3 of Fig. 4; Fig. 4 is a view in elevation, partially in section, illustrating two chemical tanks and a single valve in the water inlet pipe in controlling relation to the chemical discharge pipes, this view being partially in section and partially in elevation; and Fig. 5 is a sectional view on line 5—5 of Fig. 4.

Like parts are indicated by similar characters of reference throughout the different figures.

The tank 1 is of any suitable formation and is provided with a central settling chamber 2, which may be in the form of a stand pipe. This chamber has no communication with the tank space surrounding it, except at the bottom, in accordance with well known practice.

The water to be treated is supplied from the city mains or from any other suitable source and flows through the riser 3 that may pass upwardly through the settling chamber 2 to the place where the raw water is to be discharged into such chamber. This chamber is provided with a continuation in the form of a funnel 4 at the upper end of the chamber.

As will be more fully hereinafter set forth, the water passing from the pipe 3 into the settling chamber 2 controls the flow of chemical from the chemical tanks 5, 5' into the funnel 4 so that the chemical will flow in quantities proportional to the amount of raw water discharged into said funnel. The mixture of water and chemical is initiated in the funnel and is promoted by the upright perforated interleaved baffle plates 6, 7 carried by the horizontal imperforate passage walls 8, 9 and the horizontal perforated baffle plates 10, 11. The baffle plates form a part of the subject matter of my copending application Serial No. 487,121, filed July 23, 1921.

The chemicals are supplied to the chemical tanks from separate chemical supply

tanks of which one 12 is shown. The piping and other equipment pertaining to each chemical tank are like that pertaining to the other. The chemical supply tank 12 shown discharges into its chemical tank through the supply pipe 13, the supply tank receiving unemployed chemical back from the chemical tank through the return pipe 14. The chemical tank 5' also has a supply pipe 13' and a return pipe 14' pertaining to its own supply tank, not shown. Each supply pipe 13, 13' is desirably continued nearly to the bottom of its corresponding chemical tank 5 or 5' and is there provided with a horizontal outlet slot opening 13² through which the chemical is distributed in sheets initially in a horizontal direction. Each chemical tank has a flaring side, as indicated at 13³ in Fig. 2, so that the sheet of chemical coming into the tank is given a reverse motion, the inlet end of the pipe being at the side of the chemical tank opposite the flaring 13³. The discharge pipes leading from the chemical tanks are desirably also arranged as illustrated in Fig. 2 where the discharge pipe 14 is shown as terminating near the top of the tank 5. The level of the chemical in the chemical tank is defined by the position of the upper end of the pipe 14 and is maintained at this level as long as the corresponding pump (15) is in operation, such pump serving to maintain the flow of chemical into the corresponding chemical tank in sufficient volume to be in excess of that required so that the level of the chemical in the corresponding chemical tanks 5, 5' is maintained constant.

The upper end of pipe 3 is provided with 40 weir ports 16 that are elongated lengthwise of the pipe. A weighted valve 17 has a range of movement extending through the zone of said ports and slightly on either side thereof, the valve functioning to completely close said pipe and to fully open 45 said ports or partially open the same, depending upon the head or pressure of the water flowing upwardly in said pipe. Valve 17 has an upwardly extending stem 50 18. This stem is formed with as many upright racks 19, 19' as there are chemical tanks 5, 5', each rack being individual to a tank. Pinions 20, 20' are respectively in mesh with said racks. Other upright racks 55 21, 21' are respectively in mesh with said pinions. The lower ends of the latter racks are joined by a horizontal cross piece 22, and their upper ends by a horizontal cross piece 23. This latter cross piece is extended 60 at both ends and carries pins 24, 24' that carry upright pipes 25, 25'. The pinions cause the racks 21, 21' and the pipes 25, 25' to move oppositely to the valve 17 and the racks 19, 19'. Pipes 25, 25' pass through 65 and are in sliding relation to the bottom

of the corresponding chemical tanks 5, 5', there being stuffing boxes 26, 26' in said tank bottoms through which the pipes 25, 25' may slide. These pipes discharge the chemicals into the funnel 4. These pipes 25, 25' have 70 ports 27, 27' in the region of the upper levels of the chemicals in the tanks 5, 5'. The pressure exerted by the weighted valve 17 upon the water in the pipe 3 counteracts the pressure of this water upon the valve sufficiently 75 to enable the valve to control the position of the pipes 25, 25' and their ports 27, 27'. The arrangement and operation of these parts is such that when the bottom of the valve 17 is at the bottom of the ports 16 80 that the bottoms of the ports 27, 27' are above the chemical in the tanks 5, 5'. When the bottom of said valve is above the bottoms of the ports 16 the bottoms of the ports 27, 27' are below the upper levels of the 85 chemicals. The ports are so proportioned and interrelated that the amount of water passing through the ports 16 and the amounts of chemicals flowing through ports 27, 27' into pipes 25, 25' and through said 90 pipes into the funnel 4 are in fixed proportion, the volumes of chemicals flowing through the pipes increasing or decreasing with any increase or decrease of the flow of water. The water and chemical in varying volume but in fixed proportion, are initially received in the funnel 4 from which they are passed to the channel containing the baffles 6, and 7 and from this channel through the perforated baffles 10, 11 as 100 hitherto fully described.

While two chemical tanks and attendant equipment are shown, it is obvious the number may be increased or reduced.

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:—

Liquid treating apparatus including a 115 source of liquid furnishing liquid to be treated under pressure; a pipe communicating with said source; a valve in said pipe operated by the liquid, the pipe having a port closed by said valve and also opened to varying extents by the valve according 120 to the pressure exerted upon the valve by the liquid; a settling chamber into which the liquid to be treated is discharged through said port; a chemical tank; a chemical pipe movable up and down and having a port 125 at one end near the level of the chemical in the chemical tank and communicating with the chemical tank to receive chemical therethrough, said chemical pipe discharging at its other end into the settling cham- 130

ber; an upright rack coupled with said valve; an upright rack connected with said chemical pipe; and gearing in mesh with said racks and serving to move said chemical pipe oppositely to the valve whereby the extent of the port in the chemical pipe through which chemical may flow is in-

creased as said valve increases the extent of the liquid port through which liquid to be treated may flow and vice versa. 10

In witness whereof, I hereunto subscribe my name this 12th day of March A. D., 1923.

INOS B. TANNER.
